UNITED STATES PATENT OFFICE.

LAWRENCE J. ZAHN, OF LONG ISLAND CITY, NEW YORK, ASSIGNOR TO INTERNATIONAL POSTAL SUPPLY COMPANY, OF BROOKLYN, NEW YORK.

MOISTENING DEVICE FOR MAILING MACHINES.

Application filed August 20, 1926. Serial No. 130,418.

This invention relates to a moistening device, particularly adapted for use in connection with a mail sealing and stamp canceling machine. In a sealing apparatus for this purpose, means must be provided for moistening the flap of the envelope, so that the adhesive substance thereon will be moistened sufficiently, so that the envelope may be quickly sealed, as it passes over the sealing 10 rollers.

It is the object of my invention to provide a moistening device which will perform the functions of carrying a moistening liquid, such as water, to the envelope, in a highly 15 efficient manner. Another object of my invention is to provide a moistening apparatus which will give long life and service, and one in which the parts may be quickly adjusted for suitable operation.

20 These and other objects will be apparent to one skilled in this art, after a reading of the specification taken in connection with the annexed drawing, wherein—

Figure 1, is a partial side view on a much 25 reduced scale of a machine to which my improvement is adapted,

Figure 2, is a plan view of the moistening device per se, including the drive wheel with 30 which it is associated,

Figure 3, is a side view of Figure 2,

Figure 4, is an enlarged fragmentary view 35 of a section of the chain comprising the moistening device, while

Figure 5 is a substantially full size view 40 of one of the driving members or sprockets for rotating the chain.

Referring now to the details, wherein like 45 numbers refer to corresponding parts in the drawing, 1 is a frame of a machine to which a feed table 2, is attached. The letters to be sealed are laid on the table 2, and fed forward by a feed roller 3, driven by any satisfactory means such as a belt connected to a pulley wheel 4. The machine comprises 50 the usual pressure and feed rollers 5, 6, 7, 8, etc., and a meter 9, which is controlled by a printing die, so that whenever a letter is cancelled it is counted up on the meter 9. As is usual in such machines the letter after 55 passing by the meter 9, is guided by the guide member 10, into the stacker 11.

Attached to the frame 1, as by screws 14, is a small receptacle 12, suitable for carrying a liquid, such as water, a filling vessel

13 is connected with the receptacle 12, by 55 a pipe 15.

A support member 18, having preferably integral therewith a bearing hub 17, is attached to the frame 1, that is to say, the outside portion of the bearing 17, fits in 60 the frame 1. Carried by the bearing 17, is a shaft 16, connected with any satisfactory driving means used in machines of this character. On the outer end of the shaft 16 is the pulley wheel 4, already referred to. 65

On the support member 18, there is carried two studs 25 and 32, preferably one of these studs is adjustable longitudinally of the support, as by means of a slot 26, and a nut 27. On the stud 32 is pivotally supported 70 a driving member or sprocket 28, while on the stud 25 is rotatably supported a similar driving member or sprocket 24, and carried by the sprockets 24 and 28 is a chain 19. The chain 19, is made up of alternate links comprising side bars 20 and 21, between the extremities of which are positioned connecting bars 22. The bars 20 and 21, carry an eyelet bushing 23, so that the connecting bar 22, is pivoted on this eyelet as is more clearly 75 shown in Figure 4. Each eyelet carries a brush 36, preferably made of hair or bristles or other satisfactory material, which are formed in the shape of hairpin loops, and passing around these loops, preferably a 80 number of times is a binding member 33, preferably of copper wire, which can be readily soldered as at 34 to the end of the eyelet and to the bar 21. As shown in Figure 4, a space 34 is purposely indicated so as 85 to show the binding wire 33 in position.

Since the bearing stud 25 is adjustable with respect to the stud 32, the proper tension on the feed chain may be obtained. The support 18, together with the bearing bushing 17, may be adjusted longitudinally of the shaft 16, so as to give the proper pressure 90 on the ends of the brushes 36, as they pass by the inner flap of the envelope, this adjustment also provides for proper setting of 95 the brushes as they wear with use.

As will be seen in Figure 3, the stud 32 carries the pinion 31 connected to an idler 30, and this in turn to a driving gear 29, on 100 the shaft 16.

It will be understood that when the parts are assembled as shown in Figure 1, the lower extremity of the chain 19 dips into the 105

receptacle 12 a suitable distance and the brushes 36 pick up the moistening fluid, such as water, and carries it to the flap of the envelope. While I have shown the chain 19, 5 in a vertical position in Figures 2 and 3, it is to be understood that in practice the support 18, together with the chain 19, may take an angular position, to secure proper working relation of the parts.

10 The rotary members 24 and 28 are preferably constructed so that the side 35 is of a length to fit the connecting link 24 and the teeth 38 are adapted to pass over the rounded ends of the connecting links 22, so that 15 the driving is all applied to the connecting links 22, and not directly on the bearing eyelets 23 or other parts.

While I have shown a preferred form of applying my invention it is to be understood 20 that the details may be varied without departing from the spirit or scope of the appended claims.

Having thus described my invention, what I claim is:

25 1. In a moistening device for the purpose described, a support, rotary operating members mounted at each end of the support, an endless chain carried by said operating members, a bearing carried by said support, a drive shaft passing through said bearing, driving means connected between said shaft and at least one of said operating members and moistening brushes carried by said endless chain and adapted to be moved through 30 an associated receptacle containing a liquid.

40 2. In a moistening device for the purpose described a support, rotary operating members mounted at each end of the support and means for altering the distance between 45 their axial centers, and an endless chain carried by said operating members, a bearing carried by said support, a drive shaft passing through said bearing, driving means connected between said shaft and at least one of said operating members, moistening brushes carried by said endless chain and adapted to be moved through an associated receptacle containing a liquid, said support being adjustable longitudinally of the shaft 50 as and for the purpose described.

55 3. In a moistening device for the purpose described, a support, a pair of sprocket wheels mounted for rotary movement at a spaced distance apart on the support which distance may be varied at will, a link belt chain carried by said sprockets, a bearing carried by said support, a drive shaft passing through said bearing, driving means connected between said shaft and at least 60 one of said sprockets and moistening brushes carried by the links of said chain said brushes adapted to be moved through an associated receptacle containing liquid.

65 4. In a moistening device for the purpose described, a support, a pair of sprocket

wheels mounted for rotary movement at a spaced distance apart on the support, which distance may be varied at will, a link belt chain carried by said sprockets, a bearing carried by said support, a drive shaft passing through said bearing, driving means connected between said shaft and at least one of said sprockets, and at least one moistening brush carried by alternate links of said chain, said brushes adapted to be moved 70 through an associated receptacle containing a liquid.

5. In a moistening device for the purpose described, a support, a bearing preferably integral with said support, a drive shaft 80 passing through said bearing, a pulley on the outer end of said shaft, driving means positioned between said pulley and said bearing, rotary operating members mounted apart on the support and means for changing the distance between their axial centers, connecting means between said driving means on the shaft and at least one of said rotary members, a link chain carried by said operating members and brushes carried by a portion of 85 said links, said brushes adapted to be moved through an associated receptacle containing a liquid.

6. In a moistening device for the purpose described, a link chain composed of alternate 90 pairs of laterally spaced links and a connecting link having its opposite ends positioned between said alternate pairs of links, eyelets passing through the ends of said links and acting as bearings for said connecting links, brushes carried in said eyelets, sprocket 95 wheels to receive said links, a support for the sprockets and means for driving at least one of said sprockets so said brushes will pass through a liquid carried in an associated receptacle.

7. In a moistening device for the purpose described, a link chain composed of alternate 100 pairs of laterally spaced links and a connecting link having its opposite ends positioned between said alternate pairs of links, eyelets passing through the ends of said links and acting as bearings for said connecting links, brushes carried in said eyelets, said 105 brushes being composed of a plurality of hairpin loops bound together at the loop and the binding means being attached to one of said laterally spaced links, sprocket wheels to receive said links, a support for the sprockets and means for driving at least one of said sprockets so said brushes will pass through a liquid carried in an associated receptacle.

8. In a moistening device for the purpose 110 described, a link chain composed of alternate pairs of laterally spaced links and a connecting link having its opposite ends positioned between said alternate pairs of links, eyelets 115 passing through the ends of said links and acting as bearings for said connecting links,

brushes carried in said eyelets, sprocket wheels having faces between the teeth of substantially the same length as the straight portion of said connecting link and the teeth 5 of said sprockets being formed to fit the curved ends of the connecting link for the purpose described, a support for the sprockets and means for driving at least one of said sprockets so said brushes will pass 10 through a liquid carried in an associated receptacle.

9. In a moistening apparatus including a receptacle for a liquid and driving means, a chain having an end extending downward 15 into the receptacle, said chain comprising alternate links each carrying an eyelet in both ends, a connecting link pivotally mounted on each eyelet, brush elements permanently positioned in the eyelets, sprocket wheels 20 formed to fit said connecting links and means extending between at least one sprocket wheel and the driving means for operating the chain.

10. In a moistening apparatus including 25 a receptacle for a liquid and driving means, a chain having an end extending downward

into the receptacle, said chain comprising alternate links each carrying an eyelet in both ends, a connecting link pivotally mounted on each eyelet, brushes composed of a plurality of hairpin loops bound together at the loops and positioned in the eyelets, said binding means being anchored securely to the eyelet and cooperating link, sprocket wheels 30 formed to fit said connecting links and means 35 extending between at least one sprocket wheel and the driving means for operating the chain.

11. In a moistening apparatus including a receptacle for a liquid and driving means, a 40 chain having an end extending downward into the receptacle, said chain comprising alternate links each carrying an eyelet in both ends, a connecting link pivotally mounted on each eyelet, brush elements permanently 45 positioned in the eyelets, rotary operating means for carrying said chain and connecting means between said driving means and said rotary operating means.

In testimony whereof, I affix my signature.

LAWRENCE J. ZAHN.
